SHOE-BOTTOM-COATING MACHINE

John R. Oliver, Beverly, Mass., assignor to United Shoe Machinery Corporation, Flemington, N. J., a corporation of New Jersey

Application October 9, 1940, Serial No. 260,478

1 Claim. (Cl. 91—43)

This invention relates to shoe-bottom-coating machines and is herein illustrated as embodied in a machine for coating one face of a flange adjacent to the bottom of the shoe and extending around a portion of the periphery thereof.

Certain shoes of the stitchdown type are manufactured by forming an outwardly turned flange adjacent to the inseam around the periphery of the bottom of the shoe, or at least that portion of the bottom which is forward of the heel breast line, and by securing to this flange by adhesive a strip of beveled welting. In order to make such shoes light and flexible, the above-mentioned flange is both narrow and thin and is tapered toward its edge. It may, for example, be only one eighth of an inch in width and as little as one sixteenth of an inch thick at its base. One coating of the cement which is to attach the welting is applied to the outer face of this flange and, when this is done by turning the shoe to present the successive portions of the flange to a coating member such as an extruding nozzle, considerable care is required in handling the work because of the tendency of the flange to jump over the nozzle, and this difficulty is accentuated when overlapping seams such as are usually found between the vamp and the quarter are encountered.

To provide a coating machine facilitating this operation is an object of this invention. Machines of the extruding type are in common use which have a feed roll engaging the side or bottom of the shoe and which are provided with depending nozzles for the application of cement to either the marginal portion of the bottom or to some nearby area. In such machines an inverted shoe is held up by the operator against the nozzle and is pressed laterally to contact with the feed wheel and it is turned by the operator as he presents successive portions of the periphery to the nozzle. The illustrated machine in accordance with the features of the invention is of the general type of those just described and is arranged to facilitate the presentation of the work. It will be understood that the above-mentioned flange extends outwardly from the side of the shoe at a sharp angle thereto, thus forming a crease. Accordingly, the nozzle of my improved machine is tapered or pointed so that it will enter this crease, and is provided with a lateral outlet to deliver the cement to the adjacent outer side of the flange. In view of the extreme flexibility of this flange, however, it is desirable to mount the nozzle for swinging movement so as to accommodate the changing relation of the crease, and the flange adjacent thereto, to the

bottom surface of the shoe as the latter surface is brought into engagement with the feed wheel. This feed wheel serves also to guide the shoe as it is turned to carry the successive portions of the flange past the nozzle. The desired result is obtained partly by reason of the mounting of the nozzle upon a pivot which is above the work substantially in line with the axis of the feed wheel, this pivot extending substantially parallel to the direction of feeding movement of the portion of the work being treated.

These and other features of the invention will be best understood from a consideration of the following description taken in connection with the accompanying drawings, in which

Fig. 1 is a side elevation of the work-engaging portion of my machine;

Fig. 2 is an enlarged view in a similar direction showing the nozzle and its mounting;

Fig. 3 shows this nozzle as viewed in the direction of the arrow III on Fig. 1;

Fig. 4 is a greatly enlarged view of the tip of the nozzle shown in engagement with the flange of the work; and

Fig. 5 is a detail of the grooved lateral face of the tip of the nozzle viewed in the direction of the arrow V on Fig. 2.

The work-engaging parts of the machine are, as shown, embodied in a machine of the type illustrated in Letters Patent of the United States No. 2,100,341, granted November 30, 1937, on the application of W. L. MacKenzie. As in that machine, a feed wheel 10 is mounted upon a swinging carrier 12 which is pivoted about an axis at a substantial distance below the feed wheel between sides of a frame of which one side 14 is shown in Fig. 1. This swinging movement is parallel to the plane of the paper, in the direction of the double-pointed arrow 16 and is limited in one direction by the engagement of a flange 18 on the carrier 12 with a stop 20 mounted on the frame. In this carrier 12 are mounted driving means 22 arranged to rotate the feed wheel to carry the portion thereof, which contacts the bottom B of a shoe S, away from the observer.

In a manner generally similar to that shown in the patent, a nozzle 24 is supported upon an outwardly extending rod 26 which is clamped in an arm 28 pivoted to the frame at a point some distance to the right of the nozzle. Vertical adjustment to permit the nozzle to be brought into the proper relation to the feed wheel is accomplished by a threaded stop screw 30 on the arm which engages a flange 32 on the frame and a spring (not shown) urges the arm 28 counter-

clockwise toward the position shown. On this rod 26, there is clamped a hanger 34 which is forked at its lower end to provide horizontal arms 36 and 38 extending toward the observer, and a plate 40 forming part of the nozzle is supported upon the upper sides of these arms and is held in position thereon by a clamp 42 pivoted on a rod 43 and engaging the upper surface of the plate. The work-engaging portion of the nozzle comprises a tapered plate 44 which has a passage 46 leading to an outlet opening 48 and this plate is attached by dowel pins 50 and a screw 52 to the side of a triangular portion 54. This portion 54 has spaced, upwardly-extending arms 56 and 58 (Fig. 3) through which is passed a pivot pin 60 extending also through a hub portion 62 which is integral with and hangs below the plate 40. The tapered portion 44 of the nozzle is urged in a counterclockwise direction, as viewed in Figs. 1 and 2, by a spring 64 coiled around a head 66 of the pivot pin and which at one end engages the arm 58 and at its other end abuts a pin 68 (Fig. 2). This movement, when no work is present, is limited by a stop screw 70 threaded in a boss 72 extending laterally from the forked member 54.

The delivery of cement under pressure to the nozzle is effected by means of a hollow neck 74 having a flange 76 by means of which it is screw-attached to the upper side of the plate 40. This neck has a passage 78 which communicates with a recess 80 (Fig. 2) in the upper side of the plate 40 and thence by an inclined passage 82 to a recess 84 (Fig. 3) on the inside of a detachable plate 86 which is held by screws upon the hub 62. From this recess 84, the cement is delivered to the passage 46 in the tapered portion 44 through a flexible capillary tube 88 clamped on the hub 62 by means of the above-described plate 86 and communicating with the recess 84 therein. The lower end of the tube, protected by a cover plate 89, slidably engages a passage 90 in the plate 44 which is in direct communication with the passage 46 therein. It will be noted from Fig. 5 that the outlet slot 48 extends diagonally across the bottom surface of the nozzle plate 44 in a direction extending upwardly and forwardly from the passage 46. As a result, when the work is

presented progressively to the nozzle, the flange F on the shoe will drag across the inclined outlet slot and the cement will be pulled upwardly in the groove 48 and will more perfectly be distributed across the outer face 92 of this flange F. A forwardly-extending rounded lip 94 on the tip of the nozzle rides easily in the crease which is adjacent to the flange F.

In the use of the machine, as successive portions of the outer surface 92 of the flange F are presented to the nozzle the operator will press the bottom B of the shoe against the feed wheel 10 and will raise the shoe to bring the flange F into contact with the nozzle. Moving the shoe away from the observer in Fig. 1, the pressure exerted by the operator will be in a general upward direction, resolving itself into two components, one extending inwardly toward the feed wheel and the other extending diagonally toward the nozzle, with the result that the part of the upward pressure which is exerted toward the nozzle is substantially in line with the pivot 60 and, therefore, has practically no effect in swaying the nozzle toward and away from the machine. The nozzle being held by the spring 64 against the flange F will ride easily along this flange, regardless of any overlapping seams that may be encountered, and this riding of the nozzle upon the work is facilitated by the rearwardly extending lip 94. Such an arrangement permits the spring 64 to be relatively light, and enables the operator to present the very narrow and flexible flange F without difficulty.

Having described my invention, what I claim as new and desire to secure by Letters Patent of the United States is:

In a shoe-coating machine, a depending nozzle for applying cement to one face of a portion of a shoe, said nozzle having a tapered end portion provided with a side face across which may slide the face to be coated, said nozzle face having an outlet groove extending diagonally along it from a point adjacent to the lower end of the nozzle transversely and upwardly whereby a piece of work drawn across said groove tends to pull the cement upwardly therein.

JOHN R. OLIVER.
